BRASSIERE

Pearl J. Steinmetz, Evanston, Ill., assignor to The H. W. Gossard Co., Chicago, Ill., a corporation of Illinois

Filed Apr. 13, 1959, Ser. No. 805,792

2 Claims. (Cl. 128—494)

This invention relates to brassieres and it has for its object to provide a novel and improved garment of this type which may be worn with perfect comfort and freedom of movement to the wearer under all conditions of use.

Another object of the invention is to provide an extremely light weight self-adjusting brassiere which is adapted to mold and support the busts and at the same time adjust itself in conformity with bending and stretching movements of the body.

Still another object is to provide a brassiere of the type specified which is simple in construction and is cheaper to manufacture than previous brassieres of comparable functional characteristics.

Various other objects and advantages will be apparent as the nature of the invention is more fully disclosed.

The brassiere of the present invention comprises a front portion having a pair of connected bust pockets preferably composed of soft inelastic fabric of generally rounded cup-shaped contour, and a marginal front body portion composed of two-way stretch elastic fabric which is stitched to the outer rounded edges of said bust pockets and forms a frame of two-way stretch fabric extending downwardly from the central upper apexes of the bust pockets, down the outer sides thereof, and longitudinally beneath said bust pockets.

Under-arm flaps or end sections preferably of inelastic material are stitched to the outer side edges of the two-way stretch marginal front body portion. Conventional fastening means are provided for connecting these end sections together at the back, and at least one of said end sections may have an elastic insert for tensioning the garment resiliently upon the body. In the embodiment illustrated herein a narrow band of one-way longitudinally stretchable tape lines the lower longitudinal edge of the marginal two-way stretch front body portion below the bust pockets for fitting the brassiere snugly upon the figure.

Shoulder straps preferably composed of inelastic tape each have one end secured to an individual end section of the brassiere and the other end secured to the two-way stretch elastic fabric at the central upper apex of an individual bust pocket, so that tension on said shoulder straps is communicated directly to said two-way stretch elastic fabric.

When the shoulder straps exert an upward pull on the central upper apexes of the brassiere, as when the wearer raises her arms or stretches backwardly, said shoulder straps exert not an upward pull directly on the inelastic bust pockets, but rather a pull on the two-way stretch elastic fabric which "frames" said bust pockets. Since the bottom (horizontal) edge of the brassiere beneath the bust pockets is snug albeit resiliently anchored in place on the body, the aforesaid upward pull of the shoulder straps is distributed bias-wise over the two-way stretch fabric "frame" according to the direction and extent of said pull.

2

Thus, in the course of normal or even strenuous physical activity the application or release of any sort of tension on the two-way stretch fabric "frame" of the brassiere, whether due to bending, stretching, twisting or breathing, is compensated by an accommodating elongating or contracting adjustment of said "frame" which eliminates strain on the busts and shoulders and insures perfect comfort and freedom of movement to the wearer in all positions of the body.

10 The various features and advantages of the invention are described more in detail in connection with a preferred embodiment illustrated in the accompanying drawing, in which:

Fig. 1 is a front perspective view of a brassiere embodying the invention;

Fig. 2 is a rear perspective view of said brassiere;

Fig. 3 is an enlarged fragmentary plan view of the two-way stretch elastic fabric employed in the marginal front body portion of the brassiere;

Fig. 4 is a detail section taken on line 4—4 of Fig. 1; and

Fig. 5 is a detail section taken on line 5—5 of Fig. 1.

The brassiere shown in the drawing comprises a front portion including bust pockets 1 and 2 of soft inelastic fabric made in three pieces of material shaped and stitched as illustrated in a generally rounded cup-shaped contour and connected together by the narrow inelastic median band 3.

A marginal front body portion composed of two-way stretch elastic net fabric, illustrated in Figs. 1 and 3 as being made in three pieces 4, 5 and 6, is stitched to the outer edges of bust pockets 1 and 2, and forms a frame of two-way stretch fabric composed of a first part extending downward and outward from the central upper apexes 7 and 8 of each of said bust pockets along the upper edges, a second part extending downward from the first part along the outer sides thereof and a third part extending from the second part longitudinally all the way across below said bust pockets and their median band 3.

Under-arm flaps or end sections 9 and 10 of inelastic fabric are stitched to the outer side edges of the second parts marginal front body pieces 4 and 5. The end section 10 has an elastic insert 12, and the two end sections have suitable cooperating fastener members such as hooks and eyes for resiliently connecting the outer ends of said end sections together at the back of the brassiere when the garment is in wear.

The marginal front body portion of the brassiere may 50 be composed of any suitable two-way stretch elastic fabric, for example the net fabric shown in Fig. 3 consisting of parallel elastic warp threads 13 interwoven by the threads 14 in the open mesh structure illustrated, which is stretchable both horizontally and vertically as viewed in Fig. 3.

A lining of narrow one-way longitudinally stretchable tape 15 is stitched to the lower longitudinal edge of the marginal body portion 4—5—6 below the bust pockets 1 and 2 for yieldingly tensioning the brassiere snugly upon 60 the body beneath the busts.

Shoulder straps 16, preferably composed of inelastic tape with adjusting clasps 17, each have one end stitched to an individual end section 9 or 10 of the brassiere, and the other end stitched to the two-way stretch elastic net 65 fabric pieces 4 or 5 adjacent the central upper apex 7 or 8 of an individual bust pocket 1 or 2 as illustrated in Figs. 1 and 2.

When in wear, the brassiere fits snugly but yieldingly and comfortably on the body, the two-way stretch elastic of the marginal front body portion of the garment expanding and contracting easily as the wearer breathes.

As will be apparent from Figs. 1 and 2, any upward pull on the shoulder straps is applied directly to the two-way stretch elastic fabric of said marginal body portion which provides a bias pull insuring proper automatic adjustment, under-arm control, and complete shoulder strap comfort, as described above.

Although a specific embodiment is described and shown herein for purposes of illustration, it will be evident to those skilled in the art that the invention is capable of various modifications and adaptations within the scope of the appended claims.

The invention claimed is:

1. A brassiere comprising a front portion having a pair of bust pockets composed of inelastic material, a median band of inelastic material connecting said bust pockets, a marginal front body portion composed of two-way stretch elastic fabric secured to said bust pockets and having a first part extending from the central part of the upper edge of each of the bust pockets angularly downward and outward along said upper edge, a second part extending from the first part downwardly along the outer side edge of the bust pocket and a third part extending from said second part longitudinally below said bust pockets and said median band all the way across

5
10
15

the space between the second parts and connected to the lower edges of said bust pockets and said median band, end sections secured to the outer side edges of the second parts, means for resiliently connecting the outer ends of said end sections together at the back of the brassiere, and inelastic shoulder straps each having one end secured to one of the end sections and the other end secured to one of the first parts adjacent the central upper edge of one of the bust pockets whereby tension on said shoulder strap is communicated directly to said two-way stretch elastic fabric.

2. In a brassiere claimed in claim 1, a lining of narrow one-way longitudinally stretchable tape stitched to the lower longitudinal edge of said marginal body portion below said bust pockets for yieldingly tensioning said brassiere snugly upon body.
